UNITED STATES PATENT OFFICE

JOHN A. TRAYLOR, OF TIGER, COLORADO, ASSIGNOR TO THE TRAYLOR VIBRATOR COMPANY, OF DENVER, COLORADO, A CORPORATION OF COLORADO

VIBRATING APPARATUS

Application filed July 12, 1922, Serial No. 574,496. Renewed March 11, 1930.

The object of this invention is to provide a vibrating apparatus operated by alternating current, and applicable to the operation of material treating elements such as screens or jaws of ore crushers.

In the accompanying three sheets of drawings which form a part of this specification,

Fig. 1 is a plan of a screen operated by a vibrating apparatus constructed in accordance with this invention.

Fig. 2 is a side elevation of the same, the supporting frame being in section on the line II—II of Fig. 1.

Fig. 3 is a vertical section on the line III—III of Fig. 4 showing the vibrating apparatus.

Fig. 4 is a section on the line IV—IV of Fig. 3 showing the same.

Fig. 5 is a diagram of connections to an alternating and a direct current source.

Fig. 6 is a diagram of a modification in which the connections are to a two-phase alternator.

Fig. 7 is a side elevation showing a series of screens operated by the same vibrating apparatus.

Fig. 8 is an end elevation of the structure shown in Fig. 7, looking toward the right-hand end of the latter figure.

In the form shown in Figs 1 and 2 a screen 11 is the material treating member to be vibrated. It is supported on either side through brackets 12, 12 and elastic rods 13, 13 to the middle points of which the brackets are clamped. The ends of the rods have heads 14, 14 riveted thereto. The rods pass through the end members of a supporting frame 15. At one end the heads engage the outside of the frame, and at the other end the heads engage the ends of tensioning screws 16, 16 which are threaded into one of the end members of the frame. The rods pass through holes in these screws and the screws are used to tension the rods and adjust their natural period of vibration so that there will be steady action when the current is turned on and the screens are in operation. Lock nuts 17, 17 secure the screws.

The screen is vibrated through cooperating magnet members on each side. One of the co-

operating magnet members is in the form of a laminated bar magnet 20, and the other is in the form of an upper laminated U-shaped magnet 21 and a lower laminated U-shaped magnet 22, these two magnets being disposed on opposite sides of the bar magnet. The U-shaped magnet members are supported through brackets 23, 23 from the supporting frame and the laminated bars are riveted to the brackets which connect the screen with the elastic rods. Each of the bar magnets has a magnetizing coil 24, the upper U-shaped magnets have magnetizing coils 25, 25 and the lower U-shaped magnets have magnetizing coils 26, 26.

The coils on one of the cooperating magnet members are connected to a source of alternating current of any frequency, but it is not essential which set of coils are so connected. This source, in the form shown in Fig. 5, is a single phase alternating-current generator 27, but may be any two leads of any other form of alternator, and the connection is made through a switch 28 to the upper of the U-shaped magnets and the connection is made through a switch 29 to the lower of the U-shaped magnets. The connection is such that with a given direction of current the poles which are on opposite sides of the same end of the bar magnet will be of opposite polarity.

The coils on the bar magnet are connected to a source of direct current shown as a direct-current generator 30 through a switch 31. The switch is so made that these coils can be disconnected from the generator and their terminals short-circuited or closed on each other through a resistance 32 which is adjusted to prevent the coils from overheating. In this latter case either the upper or the lower of the U-shaped magnets should be omitted or its coils not energized, and the vibration is not as forcible as with the direct current on the bar-magnet coil. The vibration is stronger, however, than when the coils on the bar magnet are omitted, or their circuit is open.

In the form of connection shown in Fig. 6 a two-phase alternating-current generator 33 supplies current, one phase being 100

through a switch 34 to the coil of the upper U-shaped magnet, the same phase being also through a switch 35 to the coils of the lower of the U-shaped magnets, and the other phase being through a switch 36 to the coils of the bar magnet.

Corresponding coils in the vibrating apparatus on the two sides of the screen should be similarly connected to the source of current, and the connections may be such that they are either in series or parallel with each other as may be found desirable to prevent overheating or to pass sufficient magnetizing current.

15 In either form of connections with all of the coils energized as set forth the vibrating impulses upward and downward are equal. There are certain conditions, however, when a greater upward or downward force is desirable and this may be obtained by taking advantage of the fact that magnetic attraction is greater than magnetic repulsion. Thus, for example, in screening dry ores, if it is desirable to have the more forcible 25 stroke upward into the bed of material to be screened; only the upper U-shaped magnet will be used or its coils energized. In screening sticky or moist products where it is desirable not to force the screen up into 30 the bed of material to be screened, only the lower U-shaped magnet will be used or its coils energized.

The coils of both U-shaped magnets will be energized in the case of materials which 35 do not require a rapid up-stroke and a retarded down-stroke, or the reverse.

This apparatus has been found to give satisfactory results in which a screen two by three feet is supported at the middle points 40 of two tension rods one inch in diameter and five feet in length using twenty-five to one hundred cycle current on the U-shaped magnet and direct current on the bar magnet. Improvement over usual

45 screening apparatus results with vibrations in excess of thirty per second, and high frequencies give proportionately better results. It is not essential that the tension rods should be of metal.

50 When several screens are to be vibrated the same apparatus may be used for all. By a modified construction as shown in Figs. 7 and 8, an upper screen 40 and a lower screen 41 are each mounted on vibrating rods, and on each side the bar magnet is connected to the upper of the screens and its vibrating rod, and the cooperating U-shaped magnets are supported from a bar 42 which leads to the lower of the screens 55 and its vibrating rod. Additional screens 43, 44 are supported from the upper and lower screens respectively through rods 45, 45 and 46, 46.

What I claim and desire to secure by Letters Patent is:—

1. Mechanism for imparting to and fro movements to a member associated therewith, comprising cooperating electro-magnetic means, means connecting one of said electro-magnetic means with the member to be operated, means supporting the other of said electro-magnetic means, means for supplying alternating current to one of said electro-magnetic means, and current other than current of the same phase to the other of said means, and means for cutting off the supply of current to the last mentioned electro-magnetic means and closing the circuit of the energizing coil thereof. 70

2. Mechanism for imparting to and fro movements to a member associated therewith, comprising co-operating electro-magnetic means, means connecting one of said electro-magnetic means with the member to be operated, means supporting the other of said electro-magnetic means, means for supplying alternating current to one of said electro-magnetic means, and current other than current of the same phase to the other of said means, a resistance, and means for cutting off the supply of current to the last mentioned electro-magnetic means and connecting said resistance in the circuit of the energizing coil thereof. 75

3. Mechanism for imparting to and fro movements to a member associated therewith, comprising co-operating electro-magnetic means, means connecting one of said electro-magnetic means with the member to be operated, means supporting the other of said electro-magnetic means, means for supplying alternating current to one of said electro-magnetic means, and current other than current of the same phase to the other of said means, a variable resistance, and means for cutting off the supply of current to the last mentioned electro-magnetic means and connecting said resistance in the circuit of the energizing coil thereof. 80

4. Mechanism for imparting to and fro movements to a member associated therewith, comprising an electro-magnet, means connecting the same with the member to be operated, other electro-magnets arranged on opposite sides of the first magnet, means supporting said other electro-magnets, means for supplying to said other electro-magnets alternating current of the same phase, and to said first magnet current other than current of the same phase, and means for cutting off current to the first magnet and closing the circuit of the energizing coil thereof. 85

5. Mechanism for imparting to and fro movements to a member associated therewith, comprising elastic tension rods, means supporting the same at the ends thereof, means connecting the member to be operated with said rods intermediate the ends thereof, an electro-magnet, means connecting the same with the member to be operated, other 90

electro-magnets arranged on opposite sides of the first magnet, means supporting said other electro-magnets and means for supplying to said other electro-magnets alternatively alternating current of the same phase, and direct current to said first magnet.

6. Mechanism for imparting to and fro movements to a member associated therewith, comprising a magnetizable element, an electro-magnetic element, means connecting one of said elements with the member to be operated, means for supporting the other element, means for supplying alternating current to said electro-magnetic element, an energizing coil on said magnetizable element, and means operative to connect said coil with a supply of current other than current of the same phase as that supplied to said electro-magnetic element or to disconnect said coil 20 from said supply and to close the circuit thereof.

7. Mechanism for imparting to and fro movements to a member associated therewith, comprising a magnetizable element, an electro-magnetic element, means connecting one of said elements with the member to be operated, means for supporting the other element, means for supplying alternating current to said electro-magnetic element, an energizing coil on said magnetizable element, means operative to connect said coil with a supply of current other than current of the same phase as that supplied to said electro-magnetic element or to disconnect said coil 35 from said supply and to close the circuit thereof, and a resistance included in the closed circuit of said coil.

8. Mechanism for imparting to and fro movements to a member associated therewith, comprising a magnetizable element, an electro-magnetic element, means connecting one of said elements with the member to be operated, means for supporting the other element, means for supplying alternating current to said electro-magnetic element, an energizing coil on said magnetizable element, means operative to connect said coil with a supply of current other than current of the same phase as that supplied to said electro-magnetic element or to disconnect said coil 50 from said supply and to close the circuit thereof, and a variable resistance included in the closed circuit of said coil.

9. Mechanism for imparting to and fro movement to a member associated therewith, comprising a magnetizable element, an electro-magnetic element comprising a pair of electro-magnets located at opposite sides of said magnetizable element, means for connecting one of said elements to the member to be operated, means for supporting the other element, means for supplying alternating current of the same phase to the coils of said magnets, said coils being wound in 65 such manner as to render said magnets of

opposite polarity, a coil having a closed circuit on said magnetizable element, and means operative alternatively to close the circuit of said coil, or to connect the same with a supply of current other than current of the same phase as that supplied to said magnets.

10. In a vibrating apparatus, an element to be vibrated, a tension rod placed under predetermined tension to which said element is connected, cooperating magnets having coils thereon, means for supplying alternating current to the coils on one of the cooperating magnets, means for supplying current other than current of the same phase to the coils of the other magnet, physical connections between one of the cooperating magnets and said element and a suitable support for the other magnet.

11. In a vibrating apparatus, an element to be vibrated, a tensioned elastic support for said element, cooperating magnets having coils thereon, means for supplying alternating current to the coils on one of the cooperating magnets, and current other than current of the same phase to the coils of the other magnet, physical connections between one of the cooperating magnets and said element, and a suitable support for the other magnet.

12. In a vibrating apparatus, an element to be vibrated, a tensioned elastic support for said element, cooperating magnets having coils thereon, a source of alternating current, a source of direct current, electrical connections from the source of alternating current to the coils on one of the cooperating magnets, electrical connections from the source of direct current to the coils on the other of the cooperating magnets, physical connections between one of the cooperating magnets and said element and a suitable support for the other magnet.

13. In a vibrating apparatus, an element to be vibrated, a tensioned elastic support for said element, two cooperating magnet members, one of which comprises a pair of opposed magnets and the other of which is a magnet disposed between the pair of opposed magnets, coils on the magnet members, means for supplying alternating current to the coils on one of the cooperating magnet members, and current other than current of the same phase to the coils of the other magnet member, physical connections between one of the magnet members and said element, and a suitable support for the other magnet member.

14. In a vibrating apparatus, two elements to be vibrated in unison, tensioned elastic supports for each element, cooperating magnets having coils thereon, means for supplying alternating current to the coils of one of the cooperating magnets, and current other than current of the same phase to the coils of the other magnet, physical connections be-

tween one of the cooperating magnets and one of said elements and physical connections between the other of the cooperating magnets and the other element.

15. In a vibrating apparatus, an element to be vibrated, an elastic rod to which said element is connected; power means for vibrating said element; and means operative to place said rod under a predetermined tension, such as to move said element in synchronism with the movements imparted thereto by said power means.

16. In a vibrating apparatus, an element to be vibrated, an elastic tension rod to which said element is connected, means operative to vary the tension of said longitudinal tension rod, and power means for vibrating said element.

17. In a vibrating apparatus, an element to be vibrated, an elastic tension rod to which said element is connected, means for placing said rod under a predetermined longitudinal tension, and power means operative to effect power movement of said element in two opposite directions.

18. In a vibrating apparatus, an element to be vibrated, power means optionally operative to effect power movement of said element in either of two opposite directions, and an elastic tension rod connected to said element to effect movement thereof opposite to and in synchronism with said power movements.

19. In a vibrating apparatus, an element to be vibrated, a vibratory tensioned rod to which said element is connected, and power means optionally operative to effect power movement of said element in either or both of two opposite directions, in synchronism with the vibratory movements of said rod.

20. In a vibrating apparatus, an element to be vibrated, a vibratory tensioned rod to which said element is connected, and electro-magnetic means operable to effect power movement of said element in two opposite directions, in synchronism with the vibratory movements of said rod.

21. In a vibrating apparatus, an element to be vibrated, a vibratory tensioned rod to which said element is connected, and electro-magnetic means optionally operative to effect power movement of said element in either or both of two opposite directions, in synchronism with the vibratory movements of said rod.

22. Vibrating apparatus, comprising a member, electro-magnetic means for imparting reciprocatory movements to said member at a given frequency, and a vibratory element connected with said member and tensioned to move said member in synchronism with the movements imparted thereto by said electro-magnetic means.

23. Vibrating apparatus, comprising a member, electro-magnetic means for impart-

ing reciprocatory movements to said member at a given frequency, and a vibratory tension element connected with said member and adjusted to have a period of vibration or oscillation synchronous with the movements imparted to said member by said electro-magnetic means.

24. Vibrating apparatus, comprising a member, electro-magnetic means for imparting vibratory or reciprocatory movements to said member at a given frequency, and a tension rod anchored at the ends thereof and connected intermediate its ends to said member, said rod being tensioned to move said member in synchronism with the movements imparted thereto by said electro-magnetic means.

25. Vibrating apparatus, comprising a member, electro-magnetic means for imparting reciprocatory movements to said member at a given frequency, and a tension rod anchored at its ends and connected to said member intermediate its ends, said rod being adjusted to vibrate or oscillate in synchronism with the movements imparted to the member by said electro-magnetic means.
